REVERSIBLE RATCHET WRENCH

BACKGROUND OF THE INVENTION

1. Field of the Invention

The present invention relates to a ratchet wrench and, more particularly, to a reversible ratchet wrench.

2. Description of the Related Art

U.S. Pat. No. 6,431,031 discloses a reversible ratcheting tool comprising a handle, a head on an end of the handle, a drive member, a pawl, a ring, and a reversing plate. A transmission member in the form of a spring is mounted between the reversing plate and the pawl to convert manual pivotal movement of the reversing plate into pivotal movement of the pawl. The ratcheting tool of this design has a smaller head while providing higher torque-bearing capacity. In practice, the transmission member deforms to an excessive extent and, thus, results in unreliable ratcheting-direction switching operation between the drive member and the pawl. As a result, the switching arrangement is liable to get stuck or fails to provide reliable switching. Further, the transmission member fatigues easily due to excessive deformation and/or twist under the action of shear forces from the pawl, the ring, the head, and the reversing plate, leading to malfunction of the ratcheting tool.

DETAILED DESCRIPTION OF THE PREFERRED EMBODIMENT

Referring to FIGS. 1 through 3, a reversible ratchet wrench 10 in accordance with the present invention comprises a handle 11 and a head 12 extending from an end of the handle 11. In this example, the head 12 is substantially circular and has a small volume. The head 12 includes a compartment 13 consisting of a larger, first compartment section 131 and a smaller, second compartment section 132. A top face (not labeled) of the head 12 includes an opening 14 consisting of a substantially circular opening section 141 that is concentric with the first compartment section 131 and a non-circular (substantially rectangular in this example) opening section 142. The top face of the head 12 further includes a pin hole 16 adjacent to the opening section 142. Defined in a bottom face of the head 12 is a circular hole 15 that is concentric with the first compartment section 131 and has a diameter the same as that of the first compartment section 131. Thus, the bottom face of the head 12 is formed with a stop 15 (FIG. 3) that defines a portion of the second compartment section 132. The bottom face of the head 12 further includes a receiving hole 17 that is adjacent to the circular hole 15 and that is in communication with the second compartment section 132. The receiving hole 17 is partially delimited by the stop 151.

Rotatably mounted in the larger, first compartment section 131 of the head 12 is a drive member 20 having a coupling section 21 in an intermediate portion thereof. The coupling section 21 is fittingly and rotatably received in the first compartment section 131 and includes a plurality of teeth 211 in an outer circumference thereof. Formed on an upper end (not labeled) above the coupling section 21 is an engaging portion 22 extending beyond the circular hole 141 of the head 12. An annular engaging groove 221 is defined in an outer circumference of the engaging portion 22. Formed on a lower end (not labeled) below the coupling section 21 is a drive column 23 including a hole 231 for receiving a ball 232. The drive member 20 further includes a central through-hole 24 extending from the engaging portion 22 through the drive column 23 and having a shoulder portion 241. The through-hole 24 of the drive member 20 is in communication with the hole 231 of the drive column 23, which will be described in detail later.

A pushpin 25 is mounted in the through-hole 24 of the drive member 20 and includes an enlarged upper end 251 for manual pressing. A lower end of the pushpin 25 includes a stepped groove 252 for receiving a portion of the ball 232 when the pushpin 25 is pushed, thereby allowing disengagement of the drive column 23 from a socket (not shown). An elastic member 253 is mounted around the pushpin 25 and attached between the shoulder portion 241 of the through-hole 24 and the enlarged end 251 of the pushpin 25. The elastic member 253 biases the pushpin 25 upward for moving the ball 232 outward to an engaging position for engaging with a socket, which is conventional and therefore not further described. The ball 232 is engaged with the stepped groove 252 to prevent disengagement of the pushpin 25.

A pawl 30 is mounted in the second compartment section 132 of the head 12 and includes a toothed side facing the teeth 211 of the drive member 20. The toothed side of the pawl 30 includes an arcuate surface 31 having a plurality of teeth 311 (preferably more than ten teeth) for engaging with the teeth 211 of the drive member 20, thereby providing reliable mesh therebetween. Thus, the pawl/drive member arrangement of the reversible ratchet wrench may bear higher torque. The pawl 30 includes a recessed portion 32 in another side facing away from the arcuate surface 31.

Still referring to FIGS. 1 through 3, a ring 40 is pivotally mounted around the engaging portion 22 of the drive member 20. A tip piece 41 projects outward from the ring 40 and includes a slot 411. A notch 42 is defined in an inner periphery of the ring 40 and aligned with the tip piece 41.

A reversing plate 50 includes a hole 51 so as to be mounted around the engaging portion 22 of the drive member 20. Hence, the reversing plate 50 and the drive member 20 have a common rotating axis. The reversing plate 50 further includes a thumb piece 52. The enlarged head 251 of the pushpin 25 extends through the circular opening section 141 of the head 12 and beyond the hole 51 of the reversing plate 50 for manual operation. A positioning piece 511 projects from the reversing plate 50 in a position adjacent to the thumb piece 52. A C-clip 53 is mounted around a portion of the engaging groove 221 of the engaging portion 22 of the drive member 20, thereby retaining the engaging portion 22 of the drive member 20 to the top face of the head 12. In addition, the positioning piece 511 is extended into the notch 42 of the ring 40 to allow joint turning of the reversing plate 50 and the ring 40. An arcuate groove 521 is defined in an underside of the thumb piece 52. The thumb piece 52 further includes a receiving space 522 in communication with the arcuate groove 521 and defined by an end wall 523. It is noted that the reversing plate 50 is securely yet pivotally engaged with the engaging portion 22 of the drive member 20.

A retaining means 60 is mounted in the receiving space 522 of the thumb piece 52 and includes a substantially U-shape slide piece 61 and an elastic member 62. The slide piece 61 includes a tapered push-face 611 consisting of two faces (not labeled) separated by a tip (not labeled, see FIG. 2). The elastic member 62 is received between two limbs (not labeled) of the U-shape slide piece 61. It is noted that an end of the elastic element 62 abuts against the end wall 523 of the thumb piece 52 and that the other end of the elastic element 62 abuts against an intermediate section (not labeled) between the limbs of the U-shaped slide piece 61. In practice, the end face defining the receiving space 522 is formed by pressing to provide a structure preventing disengagement of the elastic member 62 from the receiving space 522 yet allowing movement of the slide piece 61 relative to the elastic member 62.

A pin 54 has an upper end mounted in the arcuate groove 521 of the thumb piece 52 and a lower end fixed in the hole 16 of the head 12. The arcuate groove 521 is movable relative to the pin 54 during pivotal movement of the reversing plate 50. The push-face 611 of the slide piece 61 presses against the pin 54.

A switching member 70 is pivotably mounted in the receiving hole 17 of the head 12. The switching member 70 can be actuated by the ring 40 to control the position of the pawl 30. The switching member 70 includes a receptacle 701 in a front side facing the pawl 30. A pressing member 71 and an elastic element 72 are mounted in the receptacle 701, with the elastic element 72 biasing the pressing member 71 to press against the recessed portion 32 of the pawl 30.

Hence, when the switching member 70 pivots in the receiving hole 17, the pressing member 71 moves and, thus, changes the position of the pawl 30. In this example, the pressing member 71 is a hollow pin with a blind hole for receiving a portion of the elastic element 72.

The switching member 70 further includes an engaging section 702 extending in a radial direction of the circular opening 141 of the head 12 to the tip piece 41 of the ring 40. The engaging section 702 includes a protrusion 703 engaged in the slot 411 of the tip piece 41 such that the switching member 70 is pivoted when the ring 40 is turned. By such an arrangement, when the reversing plate 50 is pivoted, the switching member 70 is turned via transmission by the ring 40 such that the pawl 30 is moved by the pressing member 71.

The switching member 70 further includes a recessed portion 704 in the front side thereof in a position adjacent to the engaging section 702. The recessed portion 703 allows easy mounting of the switching member 70 into the receiving hole 17. More specifically, in assembly, since the receiving hole 17 is partially delimited by the stop 151, the switching member 70 is tilted to allow the engaging section 702 to enter the receiving hole 17, with the recessed portion 704 providing an evasive effect for the stop 151, and the switching member 17 is then completely inserted into the receiving hole 17. The switching member 70 further includes a groove 705 in each of two lateral sides thereof. The grooves 705 provide an evasive effect while moving the pawl 30, avoiding the switching member 70 and the pawl 30 from getting stuck (see FIG. 6).

When the wrench is in a position shown in FIGS. 4 through 6, the wrench allows counterclockwise driving rotation for driving a fastener and clockwise free rotation in which the fastener is not driven. When the wrench in a position shown in FIGS. 7 through 9, the wrench allows clockwise driving rotation for driving a fastener and counterclockwise free rotation in which the fastener is not driven.

When the reversing plate 50 is moved from the position shown in FIG. 4 to a position shown in FIG. 7, the pin 54 is moved to from an end to the other end of the arcuate groove 521. The slide piece 61 of the retaining means 60 is biased by the elastic element 62 against the pin 54 to reliably position the reversing plate 50. The positioning piece 511 of the reversing plate 50 is extended through the notch 42 of the ring 40, allowing joint turning of the reversing plate 50 and the ring 40, as mentioned above. The protrusion 703 of the switching member 70 slides in the slot 411 of the ring 40 during pivotal movement of the ring 40 whereas the engaging section 702 is driven by the tip piece 41 to turn the switching member 70 counterclockwise in the receiving hole 17. After pivoting, the pressing member 71 is biased by the elastic element 72 to press against the recessed portion 32 of the pawl 30, which, in turn, urges the teeth 31 of the pawl 30 to mesh with the teeth 211 of the drive member 20. It is noted that the grooves 705 of the switching member 705 provide an evasive effect, as mentioned above. Since the switching member 70 is rigid, a reliable, secure reversing effect is obtained without the risk of deformation or malfunction of the switching member 70 that pivots in the receiving hole 17. Namely, the malfunction risk is reduced whereas the qualified product rate is increased while providing a wrench with excellent quality and prolonged life.
